DESIGN FOR A RADIO CABINET OR THE LIKE

Lester K. Franklin, Los Angeles, Calif.

Application July 5, 1941, Serial No. 101,922

Term of patent 7 years

To all whom it may concern:

Be it known that I, Lester K. Franklin, a citizen of the United States, residing at Los Angeles, in the county of Los Angeles and State of California, have invented a new, original, and ornamental Design for a Radio Cabinet or the like, of which the following is a specification, reference being had to the accompanying drawing, forming part thereof.

Fig. 1 is a front elevational view of a radio cabinet showing my new design.

Fig. 2 is a side elevational view of same.

Fig. 3 is a perspective view of same.

A portion of the device has been broken away in Figures 1 and 3 for convenience of illustration.

The characteristic features of my design reside in the portions shown in full lines.

I claim:

The ornamental design for a radio cabinet or the like, as shown and described.

LESTER K. FRANKLIN.
